KEYBOARD FOR A MICROFILM RETRIEVAL SYSTEM OR THE LIKE

Frederick G. Knowles, Rochester, N.Y., assignor to
Eastman Kodak Company, Rochester, N.Y.

Filed July 28, 1971, Ser. No. 167,077

Term of patent 14 years

Int. Cl. D14—02

U.S. Cl. D26—5

FIG. 2

FIG. 1 is a front perspective view of a keyboard for a microfilm retrieval system showing one side, the front and the top of my new design; and

FIG. 2 is a rear perspective view showing the back, the other side thereof and the top.

I claim:

The ornamental design for a keyboard for a microfilm retrieval system or the like, as shown.
